SWIVELED ATTACHMENT-PLUG.

1,103,006.

Specification of Letters Patent.

Patented July 7, 1914.

Application filed July 8, 1908. Serial No. 442,504.

To all whom it may concern:

Be it known that I, FRANK E. SEELEY, a citizen of the United States of America, residing in the city of Bridgeport, in the county of Fairfield, in the State of Connecticut, have invented a certain new and Improved Swiveled Attachment-Plug, of which the following is a specification.

The object of my invention is to provide a simple and efficient electrical attachment plug which shall be small and convenient, have a swiveling action, and be at the same time detachable. This object I attain by the construction which I will now describe.

15 In the accompanying drawings Figure 1 is a side elevation of my swiveling detachable plug in place in its socket, which is shown in section; Fig. 2 is a section of the plug on the line 2—2, Fig. 5; Fig. 3 is a section of the plug on the line 3—3, Fig. 5; Fig. 4 is a section on the line 4—4, Fig. 2; Fig. 5 is a sectional view of the plug on the line 5—5, Fig. 2; Fig. 6 is a plan view of the socket.

25 The socket part of my device will be understood upon reference to Figs. 1 and 6, and comprises an Edison screw shell S having secured to its outer margin at the open end, a collar S¹ of insulating material preferably corrugated around its circumference, while the opposite end of the shell is closed by an insulating button D carrying a central contact piece E. This contact piece has a contact surface e¹ on its outer face to make 30 contact with a coöperating connection in the socket or receptacle into which the socket S is screwed, while on the inner face of the button D the contact piece E has a spring finger e to act upon the central contact 15 of my detachable swiveling plug F. To the periphery of the button D are secured (clamped 35 between the button and the screw shell) spring fingers d to make contact with the shouldered portion of a contact shell G or

45 the plug F. The body B of this plug is of insulating material and may conveniently though not necessarily be provided with an enlarged head b with shoulder b¹ to bear on the mouth of the screw shell S, but has a cylindrical extension of reduced diameter carrying the contacts 15 and G, which are both within the interior of the screw shell, when the plug is in place. The insulating body of this plug is hollowed out longitudinally for 50 the reception and passage of the two insu-

lated wires and also for the reception of the metallic segment h, Figs. 2, 3 and 4. This segment aids in mechanically holding the contact shell G in place and in receiving the binding screw 10, for that wire end which 60 makes electrical contact with the shell G, (Fig. 2). Two screws 11, 12, threaded at diametrically opposite points into the segment h, Fig. 4, have heads bearing on the shell G, holding it to the cylindrical portion 65 of the plug. The shell G has an annular beveled shoulder 13 to coöperate with the spring fingers or clips d to make electrical connection between the shell G and screw shell S and to mechanically hold the plug in 70 place, while permitting free rotation or swiveling of the socket upon the plug. I prefer to strike up from the wall of the contact shell G a finger 14, Figs. 1 and 4, under which the wire may be passed in its way to 75 the binding screw 10 to afford a strain relief to the connection between the bared wire ends and said screw 10.

The central contact for the plug is formed by a central plug p riveted into a central hole in the end of the cylindrical insulating body, this plug being tapped at its outer end to receive the threaded binding screw 15. The outer end of this plug is recessed out to 80 form a well to receive the bared ends of the wire strands coiled about the screw 15, Fig. 5. The wall 16, which forms this recess, is cut away at a point some distance away from the hole 17, through which the wire comes 85 out through the end of the plug body, and consequently the carrying of the wire strands partially around the projecting end of the plug p, as shown in Fig. 5, provides a strain relief for that wire in the same way the finger 14 provides a strain relief for the 90 other wire.

I claim as my invention

1. The combination of a detachable swiveling attachment plug with an open ended receiving socket, comprising spring contact fingers to receive and hold the swiveling plug, a screw shell, an insulating ring secured on the outside of the open end of the shell and an insulating button closing the opposite end, said button carrying a central 100 contact with inner and outer contact faces.

2. The combination of a swiveling attachment plug having a central contact and a receiving socket comprising a screw shell, an insulating ring secured on the outside of the 105

110

open end of the shell and an insulating button closing the opposite end, said button carrying spring fingers and also a central contact with inner and outer contact faces.

- 5 3. An attachment plug, comprising a hollow insulating body with a metallic segment therein, an outer contact shell, securing means for the latter entering the segment, and a binding screw also threaded into the
10 segment, and central contact on the plug.
4. An attachment plug comprising a hollow insulating body with a longitudinal

opening for a wire and having a side contact with binding screw and a central end contact in the form of a binding screw for the wire ¹⁵ through the longitudinal opening in the body.

In testimony whereof I have signed my name to this specification, in the presence of two subscribing witnesses.

F. E. SEELEY.
